FOREIGN PATENT DOCUMENTS

KR 300995989.000 * 2/2019

Primary Examiner — Paula Allen Greene

(57) **CLAIM**

The ornamental design for an earphone clip, as shown and described.

DESCRIPTION

FIG. 1 is a perspective view of an earphone clip showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

1 Claim, 7 Drawing Sheets
